UNITED STATES PATENT OFFICE.

WILLIAM J. WOOSTER, OF BIG SPRING, TEXAS.

DEVICE FOR LINING OF CROSSEHEAD GUIDE SHOES.

Application filed September 16, 1925. Serial No. 56,780.

To all whom it may concern:

Be it known that I, WILLIAM J. WOOSTER, a citizen of the United States, residing at Big Spring, in the county of Howard and 5 State of Texas, have invented certain new and useful Improvements in Devices for Lining of Crosshead Guide Shoes, of which the following is a specification.

This invention relates to a device for facilitating the lining of crosshead guide shoes with Babbitt metal or the like bearing material.

The cross heads of steam locomotives embody guide shoes which reciprocate on guide rails, and in order to reduce friction and insure extended periods of useful service for the shoes, they are lined on their bearing surfaces with some suitable bearing material, such as Babbitt metal.

20 The primary object of the present invention is to provide a simple durable and thoroughly reliable device for facilitating the application of the bearing material to cross head guide shoes.

25 A further object is to provide a device of the above kind by means of which the bearing material may be applied on the bearing surfaces of the shoes in a uniform manner and accurately as to thickness so that no subsequent trimming or machinery 30 operation is required to prepare the shoes for use.

A still further object is to provide a device of the above kind embodying a core plate adapted to be supported between the side or longitudinal guide flanges of a cross head guide shoe, said core plate being adjustable in width so that its side edges may be positioned the required distance from said 40 guide flanges for accurately forming the bearing material of the required thickness on the inner faces of said flanges.

Another object is to provide means for supporting and retaining the shoe and core plate in proper spaced relation so that the bearing material will be applied to the bottom surface of the shoe between the flanges of the latter at the proper thickness.

Still another object is to provide means 50 to adjust the shoe laterally relative to the core plate so that the guide flanges of the shoe may be positioned the same distance from the side edges of the core plate to secure similar thickness of the bearing material on said flanges.

Other objects will become apparent as the

nature of the invention is better understood, and the same consists in the novel form, combination and arrangement of parts hereinafter more fully described, shown in the 60 accompanying drawings and claimed.

In the drawings, wherein like reference characters indicate corresponding parts throughout the several views,

Figure 1 is a side elevational view of a 65 device for facilitating the lining of cross head guide shoes constructed in accordance with the present invention and having a cross head guide shoe operatively disposed therein,

Figure 2 is an end elevational view of the device shown in Figure 1,

Figure 3 is a top plan view thereof,

Figure 4 is a substantially central longitudinal sectional view of the device shown 75 in Figure 1,

Figure 5 is a transverse section taken substantially upon line 5—5 of Figure 3,

Figure 6 is a view similar to Figure 5 taken upon line 6—6 of Figure 3, and

Figure 7 is a fragmentary plan view showing an end portion of the device with parts removed.

Referring more in detail to the drawings, the present invention embodies a rigid rectangular frame composed of guide members 5 and end members 6. The frame may also embody a bottom wall 7 for strengthening purposes, and said frame is adapted for supporting reception of the usual cross head 85 guide shoe 8, the side portions of which are adapted to rest upon the upper edges of the side frame members 5 as shown in Figures 5 so that the shoe is supported with its side guide flanges 9 projecting upwardly. 90 The frame is slightly longer than the guide shoe 8, and the end members 6 have their upper edges in a horizontal plane slightly above the plane of the bottom bearing surface of the shoe 8 when the latter is supported by the side frame members 5 as shown.

A core plate composed of sections 10 and 11 is adapted to be disposed between the guide flanges 9 of the guide shoe with its ends resting upon the upper edges of the end frame members 6 so that the core plate is supported with its bottom surface in slightly spaced relation to the bottom bearing surface of the guide shoe as clearly 110 shown in Figure 4. The core plate is divided on an oblique line as indicated at 12

to provide the sections 10 and 11, and the latter are slidably connected for relative longitudinal displacement along these oblique edges by means of a dove tail tongue and groove joint as generally indicated at 13. It is thus apparent that by displacing the sections 10 and 11 longitudinally in opposite directions the width of the core plate may be increased or decreased as desired so as to 10 position the side edges of the core plate the required distance from the inner faces of the side flanges 9 of the cross head shoe 8. Pairs of transversely aligned nuts 14 are suitably journaled or swiveled upon transverse axes in the side frame members 5, and having threaded engagement with these nuts are screws 15 arranged to have their inner ends bear against the sides of the cross head screw 8. By properly adjusting the screws 15 transversely of the frame, the cross head guide shoe may be adjusted or shifted laterally relative to the core plate so that the flange 9 at one side of the shoe is positioned the same distance from the adjacent edge of 20 the core plate as the other flange 9 thereof is positioned from the opposite edge of the core plate.

It is thus apparent that by sealing the space between the core plate and the shoe 30 at the ends of the latter with mud, wet asbestos or the like, the molten fabric metal or the like may be poured into the space so as to form a uniform lining upon the bearing surfaces of the shoe. When the metal has sufficiently cooled the core plates may 35 be reduced in width for facilitating removal of the shoe as will become apparent as the description progresses.

A pair of horizontal longitudinally 40 aligned bearing sleeves 16 and 17 are swiveled as at 18 to turn upon vertical axes, the bearing 16 being swiveled to the core plate section 10, and the bearing 17 being swiveled to the core plates 6 and 11. An adjusting screw 19 has one end portion journaled in the bearing 17 and has its other end threaded and in threaded engagement with the bearing 16. A handle or knob 20 is secured upon one end of the screw 19 for facilitating turning of the latter, and it is 45 apparent that the screw may be turned for effecting longitudinal displacement of the sections 10 and 11 of the core plate in opposite directions for increasing or decreasing the width of the core plate as found desirable.

Suitable clamping devices are provided at 50 the ends of the frame for engaging the ends of the core plates so as to rigidly maintain the latter in proper position relative to the guide shoe after being properly adjusted as to width. As shown, each of these clamping devices embodies a horizontal bar 21 having 55 downwardly and outwardly projecting bearings 22 upon the ends thereof in which the

end portions of a horizontal adjusting screw 23 are journaled, said adjusting screw having threaded portions inwardly of the bearing 22 engaging threaded apertures of clamping jaws 24. The jaws 24 project inwardly so as to enable the same to grip opposite sides of the adjacent end of the core plate as clearly indicated in several of the views, and the jaws also have upwardly projecting portions as indicated in Figure 4 70 75 which engage the outer edge of the bar 21 so that said jaws are prevented from turning about the screw 23. The threaded portions of the screw 23 are respectively of right and left hand character so that when the screw 23 is turned in one direction separation of the jaws 24 may be had, while rotation of the screw 23 in the opposite direction will effect simultaneous movement of the jaws toward 80 each other into gripping engagement with the sides of the core plate. For facilitating turning of the screw 23, a hand wheel 25 or the like may be fastened upon one end thereof. Each end frame member 6 is provided with a pair of upstanding brackets or posts 26 upon which the ends of the bar 21 rest, and these posts 26 have threaded sockets 27 into which are threaded stud bolts 28 which extends and has threaded engagement with the ends of the bar 21. It 85 is thus apparent that when the stud bolts 28 are tightened, the clamping devices may be rigidly fastened to the ends of the frame in such a manner that removal of said clamping devices with ease and facility may be 90 had.

When the lining has been applied to the bearing faces of the shoe as pointed out above, the core plate may be removed after 95 being decreased in width as was also pointed out above, upon removal of the clamping devices from the ends of the frame by disengaging the thread bolts 28 from the frame post 26. When this is done the clamping devices are separately removed as a unit, and the removal of the core plate is then allowed so that the lined guide shoe may be 100 subsequently removed with facility.

From the foregoing description it is 115 believed that the construction and operation as well as the advantages of the present invention will be readily understood and appreciated by those skilled in the art.

Minor changes may be made without departing from the spirit and scope of the 120 invention as claimed.

What I claim as new is:

1. A device for facilitating lining of cross head guide shoes with bearing material including an open frame having side members adapted for supporting reception of the shoe, a core plate adapted to be positioned between the guide flanges of the shoe, said frame including end members adapted for 125 supporting reception of the ends of the core 130

- plate whereby the side and bottom surfaces of the latter are maintained in spaced relation to the bearing surfaces of the shoe, and clamping devices rigidly secured upon the 5 ends of the frame and including pairs of jaws adapted to grip opposite sides of the ends of the core plate for rigidly maintaining the latter in proper position relative to the shoe.
- 10 2. A device for facilitating lining of cross head guide shoes with bearing material including an open frame having side members adapted for supporting reception of the shoe, a core plate adapted to be positioned 15 between the guide flanges of the shoe, said frame including end members adapted for supporting reception of the ends of the core plate whereby the side and bottom surfaces of the latter are maintained in spaced relation to the bearing surfaces of the shoe, and clamping devices mounted upon the ends of the frame and including pairs of jaws adapted to grip opposite sides of the ends of the core plate for rigidly maintaining 20 the latter in proper position relative to the shoe, and means for removably rigidly securing the clamping devices to the frame.
3. A device for facilitating lining of cross head guide shoes with bearing material including an open frame having side members adapted for supporting reception of the shoe, a core plate adapted to be positioned 30 between the guide flanges of the shoe, said frame including end members adapted for supporting reception of the ends of the core plate whereby the side and bottom surfaces of the latter are maintained in spaced relation to the bearing surfaces of the shoe, and clamping devices mounted upon the ends of the frame and including pairs of jaws adapted to grip the opposite sides of the ends of the core plate for rigidly maintaining 35 the latter in proper position relative to the shoe, and means for removably rigidly securing the clamping devices to the frame.
- 40 4. A device for facilitating lining of cross head guide shoes with bearing material including an open frame having side members adapted to be positioned between the guide flanges of the shoe, said frame including end members adapted for supporting reception of the ends of the core plate whereby the side and bottom surfaces of the latter are maintained in spaced relation to the bearing surfaces of the shoe, and means carried by 45 the frame for adjusting the shoe laterally with respect to the core plate.
- 50 5. A device for facilitating lining of cross head guide shoes with bearing material including an open frame having side members adapted to be positioned between the guide flanges of the shoe, said frame including end members adapted for supporting reception of the ends of the core plate whereby the side and bottom surfaces of the latter are maintained in spaced relation to the bearing surfaces of the shoe, and means carried by 55 the frame for adjusting the shoe laterally with respect to the core plate.
- 60 6. In a device for facilitating lining of cross head guide shoes with bearing material, a core plate comprising a plate member divided obliquely from end to end to provide a pair of sections, and manually operable means operatively connecting said sections for simultaneously displacing the same longitudinally in opposite directions for increasing or decreasing the width of the core plate at will.
7. In a device for facilitating lining of cross head guide shoes with bearing material, a core plate comprising a plate member divided obliquely from end to end to provide a pair of sections, and manually operable means operatively connecting said sections for simultaneously displacing the same longitudinally in opposite directions for increasing or decreasing the width of the core plate at will, and an interlocking slide joint between the oblique adjacent edges of the core plate sections.
8. A device for facilitating lining of cross head guide shoes with bearing material comprising a support adapted for supporting and retaining reception of the shoe, a core plate adapted to be positioned between the guide flanges of the shoe, and means for securing the core plate rigidly relative to the frame and the shoe, said core plate being adjustable in width, and means for adjusting the shoe laterally with respect to the core plate.
9. A device for facilitating lining of cross head guide shoes with bearing material including an open frame having side members adapted for supporting reception of the shoe, a core plate adapted to be positioned 120 between the guide flanges of the shoe, said frame including end members adapted for supporting reception of the ends of the core plate whereby the side and bottom surfaces of the latter are maintained in spaced relation to the bearing surfaces of the shoe, and clamping devices mounted upon the ends of the frame and including pairs of jaws adapted to grip the opposite sides of the ends of the core plate for rigidly maintaining the 125
- 130

latter in proper position relative to the shoe, and means for removably rigidly securing the clamping devices to the frame, each of said clamping devices embodying a bar and adjusting means for the jaws carried by the bar, and said frame having pairs of rigid posts upon the ends thereof adapted for supporting reception of the ends of said

bars of the clamping devices, said jaws being adjustable toward and away from each other transversely of the frame and being movable and guided between the bars and the end members of the frame. 10

In testimony whereof I affix my signature.

WILLIAM J. WOOSTER.
